UNITED STATES PATENT OFFICE.

WILLIAM MANTEUFFEL, OF ST. PAUL, MINNESOTA.

REFRIGERATOR.

1,035,370.

Specification of Letters Patent. Patented Aug. 13, 1912.

Application filed June 20, 1910. Serial No. 567,823.

To all whom it may concern:

Be it known that I, WILLIAM MANTEUFFEL, a citizen of the United States, residing at St. Paul, in the county of Ramsey 5 and State of Minnesota, have invented a new and useful Improvement in Refrigerators, of which the following is a specification.

My invention relates to improvements in 10 household refrigerators and my principal object is to secure a more uniform temperature throughout the provision chamber by means of a regulated circulation of cooled air through the ice and provision chambers.

15 In the drawings with which I illustrate my invention and which form part of my specification, Figure 1 is a sectional view of my refrigerator showing the relative position of the chambers within it and the passageways connecting them; Fig. 2 is a partial section on the line A—A, of Fig. 1, showing the details of the partition wall; and Fig. 3 is an enlarged detail of the 20 drainage trap partly in section.

25 In the above drawings, 2 is an ordinary refrigerator box and fitted with my improvements, having double walls 3 and 4 inclosing air spaces 5. The interior of the 30 refrigerator is divided into two compartments by a partition 6 having a passageway 7 below it and a passageway 8 above it, smaller than the passageway 7, and connecting the provision chamber 9 with the 35 ice chamber 10. Near the bottom of the ice chamber is a slatted grate 11 on which rests a block of ice 12. Below the grate is a funnel 13 directing the drainage from the ice 40 away from the walls and toward the center of the water pan 14. In the bottom of the water pan and extending through the floor 45 of the refrigerator, is a drain pipe 15 adapted to drain the surplus water from the bottom of the ice chamber into any suitable receptacle beneath the refrigerator. This 50 drain pipe extends above the floor of the water pan and is provided with a cap 16 fitting down over it and having openings 55 at a lower level than the top of the drain 55 by means of which a water seal is produced, maintaining a supply of water in the pan and preventing the escape of cold air from the ice chamber to the exterior of the refrigerator. The water pan maintaining a 60 constant supply of water absorbs the gases and odors from vitiated air by contact be-

tween the water in the pan and air passing in a current between the ice and provision chambers.

The partition 6 is made up of a metal 60 sheet 18 reinforced by a corrugated metal backing 19 extending vertically upon the partition and forming passageways 20 between the backing and the sheet 18. These 65 passages are closed at the top and open past the grate 11 by means of round apertures 21, and are connected with the provision chamber by similar apertures 22 at different elevations in the provision chamber. The apertures 21 serve as drains for 70 condensation forming on the cooled inner surfaces of the metal sheet 18 and also to complete the circulation of air through the passageways 20 of the partition 6. The provision chamber 9 is provided with suitable shelves 23 formed of metal screening.

75 In operation, ice is introduced into the ice chamber through a suitable door in the front of the ice box while the provision chamber is accessible through a similar separate door. 80 As the ice melts and establishes the water seal about the drain 15, the air cooled by contact with the ice, settles to the bottom of the ice chamber and passes through the aperture 7 into the provision chamber where 85 it gradually rises around the contents of the chamber. At the same time the warmer air in the top of the provision chamber passes through the aperture 8 into the ice chamber 10 replacing the cooled air that has settled 90 therefrom. The air within the passageways 20 of the partition 6 as it cools by contact with the metal sheet 18, descends, passing out through the apertures 21 and 22 thus aiding in the circulation of air within the 95 provision chamber and in the uniform cooling thereof. The aperture 8 is comparatively shallow allowing the circulation from the top of the provision chamber, of only the warmest air. By this means is prevented 100 the setting up of air currents which would tend to carry cool air over the top of the partition 6 without removing other and warmer air which was not drawn into the circulation. A slower action of the air current is produced and a resulting uniform temperature of the entire provision chamber. The slow removal of warm air through the 105 passageway 8 because of its smaller dimensions, forms an air reservoir in the provision 110 chamber. The cool air supply through a large passageway at low speed and warm air

removal through a small passageway at a higher speed tend to reduce the air currents in the cool air reservoir. The circulation of air through the apertures 22 into the passageways 20 of the partition 6 and out through the apertures 22 and 21 near the bottom of the partition produces an auxiliary circulation in the provision chamber that tends to distribute the cool air uniformly in the chamber and to break up the direct circulation of air currents from the passageway 7 to the passageway 8 and resultant unequal cooling of the parts of the provision chamber.

15 In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims:—

20 25 Having described my invention, what I claim as new and desire to protect by Letters Patent is:—

30 In a refrigerator, a refrigerating chamber for ice and a provision chamber adjacent thereto for provisions, a closed partition

separating said chambers, formed with a refrigerating chamber face and a provision chamber face, and having a circulation passageway extending across below its bottom to permit cool air from said refrigerating chamber to pass into said provision chamber at low speed, and a passageway of relatively small size above said partition at the top of said chambers adapted to the removal of the warmest air from said provision chamber at a relatively greater speed of movement to prevent air currents traversing said chamber and vertical division walls between the faces of said partition formed from a single piece of material and forming 45 passageways adjacent to the refrigerating chamber face thereof and communicating with said provision chamber through apertures in said provision chamber face to produce local air circulations in the provision 50 chamber for the uniform distribution of cool air therein.

In testimony whereof, I have signed my name to this specification, in the presence of two subscribing witnesses.

WILLIAM MANTEUFFEL.
